ALKYL SUBSTITUTED AROMATIC SULFONATES

Madison Hunt, Claymont, Del., Viktor Weinmayr, Pitman, N. J., and Mario Francesco Sartori, Wilmington, Del., assignors to E. I. du Pont de Nemours & Company, Wilmington, Del., a corporation of Delaware

Application October 15, 1947, Serial No. 780,097

5 Claims. (Cl. 260—505)

1

This invention deals with a group of alkylaromatic sulfonic acids and their salts useful as surface active agents, particularly as detergents and wetting agents.

It is an object of this invention to provide new detergent compounds of superior practical properties, especially as regards detergent power and speed of wetting.

The use of alkylated aromatic sulfonic acids as detergents as a general proposition is well known. Both sulfonated naphthalene and benzene derivatives have been indicated in the art, and the length of the alkyl chain has been varied from as low as 3 carbon atoms to as high as 20 carbon atoms, both straight-chain and branched-chain radicals being often employed.

We have now found that the limited group of compounds having the particular structure defined hereinbelow possesses outstanding qualities as detergents, being superior to hitherto described compounds as regards detergent power at low concentrations in hard water. In addition, these compounds possess very good wetting speed, which adds to their superior value from the viewpoint of practical use.

The novel compounds embraced in this invention are characterized by possessing a sulfonated m-xylene ring which is attached to the 2-carbon atom of a normal alkane having from 10 to 13 carbon atoms, the point of attachment of the alkane to said aryl ring being in a position para to one of the methyl groups. Altogether then, the compounds of this invention are defined by the formula

wherein R is a straight-chain, saturated aliphatic hydrocarbon radical of 8 to 11 carbon atoms, while X represents the sulfonic acid radical or a salt thereof.

This invention embraces the above compounds in free acid form as well as in the form of water-soluble salts thereof, as obtained for instance by neutralizing the free acid with inorganic or organic bases. For the purpose of this inven-

2

tion, the term "water-soluble" shall be construed as meaning that the compound concerned is soluble in water to an extent of at least 0.2% by weight.

5 The products of this invention are prepared by sulfonating the corresponding hydrocarbon with oleum and, if desired, neutralizing the sulfonic acid thus formed with an alkali-metal hydroxide, an alkaline-earth hydroxide, or any other alkaline agents such as primary, secondary or tertiary amines or quaternary nitrogenous bases. The alkylaromatic compounds themselves may be prepared by any suitable synthesis, such as the Friedel-Crafts reaction or reactions based on a 10 Grignard synthesis. These methods of preparation are illustrated in the following examples, which however are given merely for illustrative purposes, without any intent to limit the invention thereby.

15 The annexed drawings represent graphically the data obtained in our detergency tests on the novel compounds and reported in the tables hereinbelow.

20 EXAMPLE 1.—2(2,4-DIMETHYLPHENYL)-DECANE

A. *Synthesis of the hydrocarbon*

To a mixture of 50 parts of m-xylene and 15 parts of anhydrous hydrogen fluoride maintained at 0-5° C. in a copper vessel, 10 parts of decene-1 are added slowly, with stirring. The mass is then agitated for 18 hours at a temperature of 0-5° C. The mixture is poured slowly into 500 parts of ice water, and the upper organic layer is separated and washed with 5% sodium carbonate solution.

30 35 After removal of the excess xylene by distillation, the product is distilled. The yield of material boiling at 115°-122° C. at 3 mm. pressure is 12.8 parts. The compound gives a refractive index of $n_D^{20}=1.4906$ and density of

40 $D_{20}^{20}=0.8603$

B. *Sulfonation*

To 15 parts of the above product 27 parts of 20% 45 oleum are added slowly with agitation and cooling so as to hold the temperature at 20-30° C. After all of the oleum has been added, the temperature of the reaction mixture is raised to 40°-50° C. and held at this temperature for one-half hour. The product is poured into 90 parts of water

and 10 parts of alcohol is added in order to obtain a homogeneous solution. The mixture is drum dried to yield 50 parts of product containing about 40% active ingredient and 60% sodium sulfate. The active ingredient may be isolated in a pure state by extraction of the 40% product with hot alcohol.

Employing a similar procedure with undecene-1, dodecene-1, or tridecene-1 in place of decene, 2-(2,4-dimethylphenyl)-undecane, 2-(2,4-dimethylphenyl)-dodecane, or 2-(2,4-dimethylphenyl)-tridecane, respectively, can be prepared and sulfonated.

Instead of sodium hydroxide in the neutralization step above, the corresponding equivalent weight of any other hydroxide or base which leads to a water-soluble sulfonate may be used, for instance potassium hydroxide, calcium hydroxide, magnesium hydroxide, ammonia, monoethylamine, dimethylamine, trimethylamine, tetramethylammonium hydroxide, the corresponding ethylamines, the various ethalonamines (mono-, di-, and tri-), etc.

EXAMPLE 2.—PREPARATION OF THE HYDROCARBON BY GRIGNARD SYNTHESIS

To a suspension of 14.9 parts of magnesium in 600 parts of anhydrous ether are added 97.8 parts of n-octyl bromide in 100 parts of dry ether. The addition requires about two hours and is carried out at such a rate that the ether boils gently. The mixture is then refluxed for one additional hour. A solution of 74 parts of 2,4-dimethylacetophenone (A. Claus, Ber., 19,230) in 100 parts of dry ether is slowly added and refluxing is continued for one hour after addition is complete. The reaction mixture is then poured into ice water and acidified with hydrochloric acid. The upper layer is separated and washed with sodium carbonate solution. The ether is removed by distillation, and the residue is heated at 200° C. with 30 parts of potassium acid sulfate for 2 hours. The product is then decanted from the potassium acid sulfate and distilled. The material boiling at 135°–140° C. at 10 mm. pressure is collected. This material, which represents 56 parts, is a mixture of 2-(2,4-dimethylphenyl)-decene-1 and 2-(2,4-dimethylphenyl)-decene-2.

The above product is dissolved in 100 parts of glacial acetic acid and 0.1 part of platinum catalyst (Organic Synthesis, vol. I, page 452) are added. The mixture is reduced with hydrogen at three atmospheres pressure and at a temperature of 30°–50° C. The catalyst is removed by filtration and the acetic acid, by distillation. The mass is then vacuum distilled and the product boiling at 135°–136° C., at 10 mm. pressure, is collected. The yield is 48 parts. The product has the same physical properties as the 2-(2,4-dimethylphenyl)-decane obtained in Example 1 by hydrogen-fluoride alkylation. Analysis: Calculated for C₁₈H₃₀; C=87.81, H=12.19. Found, C=87.34, H=12.50.

This product is then sulfonated and neutralized as described in Example 1.

EXAMPLE 3

The procedure is the same as in Example 2, except that 111 parts of n-decyl bromide are employed in lieu of the octyl bromide therein mentioned. 2-(2,4-dimethylphenyl)-dodecane is obtained, which is then sulfonated and neutralized as in Example 1.

EVALUATION OF THE PRODUCTS

The evaluation of the above products for wetting power has been carried out as described in the A. A. T. C. Year Book for 1946, page 230. The wetting power is gauged by the concentration in grams of active ingredient per liter of solution necessary to wet in 25 seconds. In Table IA below, this concentration is designated as the standard wetting concentration. For detergency evaluation, the method described by O. C. Bacon, American Dyestuff Reporter, vol. 34, pages P556–P561, has been used. The results are expressed in tabular form using the per cent reflectance of light from the surface of the soiled fabric relative to the reflectance of magnesium oxide as a measure of "brightness." The detergency is tested at five different concentrations. For the purpose of these tests, water was employed containing 360 P. P. M. of alkaline earth chlorides calculated as calcium carbonate.

Using these methods, the products of this invention show outstanding detergency at low detergent concentration in hard water. This is a real advantage even though at high concentrations other closely related structures may have approximately equal activity. In addition to outstanding detergency, the products have outstanding wetting speed. This is advantageous since it enables the use of the same compound when either washing or wetting action is desired.

The following Table I illustrates the superiority of the 2,4-dimethylphenyl compounds over the corresponding phenyl derivatives as detergents in hard water.

TABLE I

Graph No.	Compound	Detergent Concentration in Per Cent					
		0	0.05	0.10	0.15	0.25	0.35
(a)	Sodium sulfonate of 2-(2,4-dimethylphenyl)-decane	36	48	49	50	51	51
(b)	Sodium sulfonate of 2-(p-methylphenyl)-dodecane	36	47	49	50	50	50
(c)	Sodium sulfonate of 2-phenyldodecane	36	36	43	44	45	45
(d)	Sodium sulfonate of 2-phenyldodecane	36	37	46	49	50	50

The above data are reproduced graphically in Figure I, wherein the individual curves have been designated *a*, *b*, *c*, and *d* to correspond with the items in the above table. It will be noted that curves *c* and *d* drop considerably below curves *a* and *b* in the region of low concentrations. This brings out the effect of the p-methyl substituent in the benzene ring. When in addition, the benzene ring carries also a methyl group in the 2-position, a marked improvement in wetting speed is obtained. This is the principal advantage of the 2,4-dimethylphenyl compounds over the 4-methylphenyl derivatives of our copending application Serial No. 780,096, and is brought out by the data in Table IA hereinbelow.

TABLE IA

Compound	Standard wetting concentration in g./l.
Sodium sulfonate of 2-(2,4-dimethylphenyl)-decane	0.42
Sodium sulfonate of 2-(p-methylphenyl)-dodecane	0.8
Sodium sulfonate of 2-phenyldodecane	0.9
Sodium sulfonate of 2-phenyldodecane	0.9

The position of the dimethyl groups on the phenyl rings is important, as illustrated by the following Table II.

TABLE II.

Graph No.	Compound	Detergent Concentration in percent					
		0	0.05	0.10	0.15	0.25	0.35
(a)	Sodium sulfonate of 2-(2,4-dimethylphenyl)-decane	36	48	49	50	51	51
(e)	Sodium sulfonate of 2-(2,5-dimethylphenyl)-decane	36	37	42	47	51	51
(f)	Sodium sulfonate of 2-(2,5-dimethylphenyl)-2,6,8,8-tetramethylnonane	36	38	44	49	49	49
(g)	Sodium sulfonate of 2-(2,5-dimethylphenyl)-2-methyldecane	36	36	38	42	50	50

The data in this table are reproduced graphically in Figure II, the curves being marked to correspond.

The contribution of a straight aliphatic chain to outstanding detergency is shown in Table III below:

TABLE III

Graph No.	Compound	Detergent Concentration in percent					
		0	0.05	0.10	0.15	0.25	0.35
(a)	Sodium sulfonate of 2-(2,4-dimethylphenyl)-decane	36	48	49	50	51	51
(M)	Sodium sulfonate of condensation product of m-xylene with propylene tetramer	36	36	37	41	40	46

For corresponding curves, see Figure III.

The position of the 2,4-dimethylphenyl group in the alkane chain is important to detergency, as shown by the following Table IV.

TABLE IV

Graph No.	Compound	Detergent Concentration in percent					
		0	0.05	0.10	0.15	0.25	0.35
(a)	Sodium sulfonate of 2-(2,4-dimethylphenyl)-decane	36	48	49	50	51	51
(k)	Sodium sulfonate of 6-(2,4-dimethylphenyl)-undecane	36	36	36	38	41	41

The corresponding graphs are given in Figure IV.

It will be understood that many variations are possible in the methods of synthesizing the novel compounds and in the choice of bases for neutralizing the sulfonic acid groups. Apart from the last-mentioned freedom of variation, however, the number of sulfonic acids falling within the scope of this invention is limited and is represented in fact by the following 4 compounds: 2-(2,4-dimethylphenyl)-decanesulfonic acid 2-(2,4-dimethylphenyl)-undecanesulfonic acid 2-(2,4-dimethylphenyl)-dodecanesulfonic acid 2-(2,4-dimethylphenyl)-tridecanesulfonic acid

These sulfonic acids may be neutralized with

alkaline compounds to give the corresponding sulfonates. Of these, the sodium sulfonates are the preferred compounds; however, the potassium calcium, ammonium and various amine or quaternary ammonium salts are also suitable.

The products of this invention are useful as detergents and wetting agents. The products show unusually high detergency at low concentrations in hard water and in addition have good wetting speed. It is expected that in practical use the concentrations employed will generally fall within the limits indicated in the above tests.

We claim as our invention:

1. A compound of the general formula

wherein R is a straight-chained alkyl radical of 8 to 11 carbon atoms, while X designates a radical selected from the group consisting of the sulfonic acid group and water-soluble salts thereof.

2. The alkylated, m-xylene alkali-metal sulfonates characterized by the formula

wherein R is a straight-chained alkyl radical of not less than 8 and not more than 11 carbon atoms, while M is an alkali metal.

3. The sodium sulfonate of 2-(2,4-dimethylphenyl)-decane.

4. The sodium sulfonate of 2-(2,4-dimethylphenyl)-dodecane.

5. A detergent composition comprising as active ingredient a compound consisting of a mono-sulfonated m-xylene attached through one of its para-positions to the 2-carbon atom of a straight-chained alkyl radical having a total of 10 to 13 carbon atoms.
